UNITED STATES PATENT OFFICE

157,981

CHERRY PITTER

Jerremiah R. Kaveney, Erie, Pa.

Application April 19, 1948, Serial No. 145,802

Term of patent 7 years

(Cl. D44—29)

To all whom it may concern:

Be it known that I, Jerremiah R. Kaveney, a citizen of the United States, residing at Erie, in the county of Erie and State of Pennsylvania, have invented a new, original, and ornamental Design for a Cherry Pitter, of which the following is a specification, reference being had to the accompanying drawing, forming part thereof.

Figure 1 is an underside perspective view of a cherry pitter, showing my new design, and

Figure 2 is a top perspective view thereof.

I claim:

The ornamental design for a cherry pitter, as shown.

JERREMIAH R. KAVENNEY.
